CLAIM

The ornamental design for a road lighting luminaire, as shown and described.

DESCRIPTION

1.1 is a top, rear, and left side perspective view of a road lighting luminaire showing our new design;

1.2 is a left side elevation view thereof;

1.3 is a right elevation view thereof;

1.4 is a rear elevation view thereof;

1.5 is a front elevation view thereof; and

1.6 is a top plan view thereof.

The broken lines in the reproductions illustrate portions of the road lighting luminaire that form no part of the claimed design.
